UNITED STATES PATENT OFFICE.

GILBERT S. VERNAM, OF BROOKLYN, AND EDWARD F. WATSON, OF YONKERS, NEW YORK, ASSIGNEES TO AMERICAN TELEPHONE AND TELEGRAPH COMPANY, A CORPORATION OF NEW YORK.

TELEGRAPH REPEATER.

Application filed May 24, 1922. Serial No. 563,313.

To all whom it may concern:

Be it known that we, GILBERT S. VERNAM and EDWARD F. WATSON, citizens of the United States, residing at Brooklyn and 5 Yonkers, in the counties of Kings and Westchester and State of New York, respectively, have invented certain Improvements in Telegraph Repeaters, of which the following is a specification.

10 This invention relates to telegraph circuits and more particularly to the type of telegraph circuits in which signals are transmitted in but one direction over the same line at one time, although the system is so 15 arranged that signals may be transmitted in either direction.

One of the objects of the invention is to provide an intermediate repeater station for 20 circuits of the above type and to provide means whereby the intermediate station can send to both the terminal stations, can receive from either terminal station, and 25 whereby signals from one terminal station, can be repeated through the intermediate station to the other terminal station. The 30 invention also includes the provision of improved means whereby the operators at any of the stations may transmit "break" signals to each other. The intermediate repeater 35 station of this invention is particularly adapted for use with a single Morse circuit of the type illustrated in a co-pending application, Serial No. 516,868, filed November 21, 1921, in the name of E. F. Watson, 40 now become Patent No. 1,541,878, granted June 16, 1925 and has been illustrated as 45 associated with such a circuit specifically. However, it is understood that it is capable 50 of embodiment in other types of single Morse lines. Other features and objects of the invention will appear more fully from the detailed description hereinafter given.

The invention may be more fully understood from the following description, together with the accompanying drawing in 55 which is illustrated a circuit diagram embodying the features of the invention.

In the drawing are illustrated two terminal stations A and B interconnected by an 60 intermediate repeater station C. ML and ML' indicate sections of a transmission line connecting stations A and B with station C. At station A a local loop L extends to a subscriber's station, in which suitable transmit-

ting and receiving apparatus may be provided; for example, a loop L is illustrated as including a schematically indicated transmitting distributor TD of a printing telegraph set and a home recording relay HRR on such a set.

The loop L at station A is balanced by means of a balancing circuit or resistance N, and windings of a polar pole changing relay PC and a polar break release relay BRR are included in the loop L and balancing 65 circuit N. At the junction point between the loop L and the balancing circuit N a connection extends to the armature of a polar receiving relay RR, which relay may, under certain conditions, be associated with 70 a section ML of the main line for transmitting signals to the loop. The connection to the armature of the receiving relay may also include an auxiliary polar relay AR for a purpose which will appear hereinafter. 75

A transfer relay TR is so arranged that it may switch the main line section ML either into connection with the receiving relay RR or into connection with the transmitting circuit controlled by the armature of 80 the pole changer PC. The connection from the main line ML to the armature of the pole changer PC includes the winding of a break relay BR. The break relay BR is a marginal neutral relay, so designed that it 85 will be unresponsive to positive or negative currents transmitted over the line in connection with ordinary signaling, but will be responsive to a current of greater amplitude transmitted over the line as a result of a break signal. The transfer relay 90 TR has two windings, one of which is controlled by the armature of the break relay BR for initially energizing the transfer relay and the other of which is a locking winding controlled by a locking contact of the transfer relay. The circuit of the locking winding is controlled by the armature of the break release relay BRR and also by the armature of the auxiliary relay AR previously mentioned. 100

The apparatus at station B is identical with that at station A and corresponding elements are represented by the same reference characters primed. Further details of 105 the apparatus will be clear from a description of the operation.

The main line sections ML and ML', which

may be termed the west line and east line respectively, are connected to station C over the contacts of a cut-out relay COR. At station C are provided the west transfer relay WTR and the east transfer relay ETR. There is also provided the west break relay WBR and the east break relay EBR. These break relays are neutral marginal relays and will not respond to the ordinary signaling currents but will respond to currents of greater amplitude. The west break relay and the east break relay are normally connected serially with the line sections ML and ML' and with the windings of a home recording relay HRR₁. Associated with the home recording relay is a circuit, including the windings of a pole changer relay PC₁ and a break control relay BCR. This circuit may be controlled by a sending key or sending distributor SD. There is also provided a receiving relay RR₁, a sender switching relay SSR and a break key BK₁. The apparatus at station C will be more readily understood from the following description of its operation.

The operation of the apparatus at the terminal stations A and B may be more readily understood by omitting the station C from the circuit and assuming that the line sections ML and ML' are directly connected to each other. Under these conditions the apparatus at stations A and B is illustrated as in condition for transmitting from station A to station B. Under these conditions, transfer relay TR' at station B is locked up to connect the line ML' to the receiving relay RR'. At station A the transfer relay TR is deenergized so that the line ML is connected to the armature of the pole changer PC. When the transfer relay TR is deenergized a negative battery is connected from the back left-hand contact of the transfer relay to the winding of the receiving relay RR so that the armature of the latter relay is maintained against its negative contact. Under these conditions, when the loop L is closed the current flows from the positive battery through the winding of the home recording relay HRR through the transmitting distributor TD, through the loop windings of the break release relay BRR and pole changer PC and through the winding of the auxiliary relay AR over the contact of the receiving relay RR to negative battery. Current also flows from ground through the balancing resistance N, balancing windings of the break release relay BRR and pole changer PC, through the winding of the auxiliary relay AR and over the contact of the receiving relay to negative battery. Obviously, the current flowing through the loop windings of the pole changer and the break release relay is substantially twice as great as that flowing through the balancing windings, owing to the fact that the positive and

negative batteries are connected in series with respect to the loop circuit. The tendency of the current flowing through the balancing windings is to shift the armature of the pole changer PC and the break release relay BRR to their upper contacts, but owing to the greater pull in the opposite direction due to the loop windings of said relays, the armatures are held to their lower contacts so that negative battery is connected through the winding of the break relay BR and over the right-hand back contact of the transfer relay to the main line section ML. The resultant line current flows over the front left-hand contact of the transfer relay TR' at station B and through the winding of the receiving relay RR' to ground. The armature of the receiving relay RR' is therefore held against its negative contact and the current conditions in the loop circuit L' are the same as described at station A, so that the armature of break release relay BRR' is held against its lower contact, thereby maintaining a locking circuit through the left-hand winding and over the right-hand front contact of the transfer relay TR'.

The conditions just described obtain during the transmission of marking signals. When a spacing signal is to be transmitted the loop L will be opened by means of the transmitting distributor TD at station A, so that no current flows through the loop windings of the pole changer PC and the break release relay BRR. The balancing windings of these relays now become effective. The shifting of the armature of the break release relay is without effect but the armature of the pole changer PC connects positive current to the main line ML so that the receiving relay RR' shifts its armature to the positive contact. The positive battery is now connected to both ends of the loop L' so that no current flows through the loop windings of the pole changer PC', break release relay BRR' and through the windings of the home recording relay HRR'. Current flows through the balancing windings of the relays PC' and BRR' in the opposite direction so that these windings are now energized in such a direction as to tend to hold their armatures against their lower contacts. Consequently, the shifting of the battery connections by means of the relay RR' is without effect upon the armatures of the pole changer PC' and the break release relay BRR'. The armature of the auxiliary relay AR' is shifted to its upper contact to provide an additional locking circuit for the left-hand winding of the transfer relay TR'. The provision of the relay AR' for this purpose is not strictly necessary, as the locking circuit will be provided over the armature of the break release relay BRR' but the provision of this additional locking circuit insures against defective operation of the

break release relay under the conditions just described.

The home recording relay HRR' may function as a sounder where the circuit is used for the transmission of ordinary Morse signals. If a printer is to be controlled by the loop L', however, the first space signal of a group will be used to release the receiving distributor (not shown) of the printer. 10 Consequently, when the relay HRR' is deenergized by reason of the fact that positive battery is connected to both ends of the loop during the first space signal of the group, the release of its armature will control the 15 release of the receiving distributor in a well known manner.

If, while signals are being transmitted from station A, it is desired to transmit signals from station B, the loop circuit L' may be opened, as, for example, by means of the break key BK'. As soon as a negative or marking signal is received from station A, negative battery will be connected to the loop over the left-hand contact of the receiving relay RR'. As the loop windings of the pole changer PC' and break release relay BRR' are deenergized, the balancing windings become effective to shift their armatures to the upper contacts. The shifting of the armature of the break release relay BRR' opens the locking circuit of the transfer relay TR', which is deenergized, so that its right-hand back contact connects negative battery to the receiving relay RR' 35 to hold the armature of the latter relay against its negative contact. At its left-hand back contact transfer relay TR' connects the line ML' through the winding of the break relay BR' to the armature of the pole changer PC'.

The armature of the pole changer is connected to positive battery at station B and it will be remembered that the changes just described occur at the time a marking signal is being transmitted from station A, so that negative battery is connected to the line ML at the latter station. This results in a current flow of approximately twice the normal amplitude through the winding of the break relay BR' over the line sections ML' and ML and through the winding of the break relay BR at station A. Both break relays are energized but the energization of the break relay BR' at station B is without effect to energize the transfer relay TR', owing to the fact that the circuit of the latter relay is held open at the armature of the break release relay BRR' and at the armature of the auxiliary relay AR'. Consequently, the transfer relay TR' at station B remains deenergized. At station A, however, the armature of the break release relay will be upon its lower contact, owing to the fact that the loop L is closed and upon the energization of the break relay BR a circuit

is completed from ground, over the contact of the break release relay BRR, over the front contact of the relay BR and through the left-hand winding of the transfer relay TR to negative battery. The transfer relay TR is energized and at its left-hand contact completes a locking circuit through its right-hand winding. By means of its right-hand armature, said relay shifts the connection of the line ML from the control of the armature of the pole changer PC into circuit with the receiving relay RR. Signals may now be transmitted from station B to station A in an obvious manner. In other words, we have a line circuit with terminal stations at each end thereof and each terminal station has transmitting and receiving apparatus thereat. There are also provided switching devices at each station for connecting a transmitting apparatus to the line at one station and a receiving apparatus to the line at the second station, so that signaling currents may be transmitted over the line in one direction. Such switching devices also function to connect the transmitting apparatus to the line at the second station and the receiving apparatus to the line at the first station to transmit signaling currents in the opposite direction. These switching devices are controlled by means 85 unresponsive to normal signaling currents but responsive to abnormal current conditions of the line.

The intermediate station repeater C is shown in the drawing in position for sending east and west, or in other words, to the stations B and A respectively. The signals at station C are initiated by the operation of a key or sending distributor SD. The operation of the distributor opens and closes 100 the circuit of the break control relay BCR and the pole changer relay PC₁. The operation of the pole changer relay causes positive and negative impulses to be sent to the coils of the home record relay HRR₁ where 105 the current divides, one half going through the left noise killer impedance, west break relay WBR, back contact of the west transfer relay WTR, the line rheostat R₂ and the left front contact of the repeater cut-off 110 relay COR to the west line ML. The other half takes a similar path through the right-hand noise killer impedance and the east portion of the apparatus to the east line 115 ML'. Thus, the impulses from the intermediate station are sent in both directions, these impulses being received at the distant stations by polar relays, such as the relays RR and RR' connected to ground. The 120 distant stations may be terminal stations as shown or other intermediate station repeaters. The coils of the home record relay HRR₁ are connected in parallel aiding so that the impulses passing through either or both of the coils will operate the relay. The 125 130

armature and contacts (not shown in the drawing) of this relay may operate a sounder or they may be connected into a printer circuit to act as a line relay. This means that the home record relay will act as the line relay for the intermediate station printer set and that all outgoing signals will be recorded on this printer. In case the operator at the west station, such as station A, should desire to send, it will be necessary for him to first break in the usual manner, causing the west transfer relay WTR and the sender switching relay SSR to be operated. A more detailed description of the breaking operation will be given later. The west line ML is then connected to ground through the receiving polar relay RR₁ so that the signals sent by the west station will be received by this polar relay. The operation of the receiving relay RR₁ opens and closes the pole changer circuit, causing positive and negative impulses to be sent through the right-hand coil of the home record relay HRR₁ to the east line ML'. The home record relay will operate the intermediate station printer set. The circuit through the left coil of the home record relay to the west line ML is open at the left back contact of its transfer relay WTR.

If the operator at the east station should desire to send it will be necessary for him to break in the usual manner. This will cause the east transfer relay ETR and the sender switching relay SSR to be operated and the polar receiving relay RR₁ will then be connected to the east line ML'. Signals from the east station, such as station B, will then operate the receiving relay RR₁ and the pole changer relay PC₁ thus repeating the signals through the left-hand coil of the home record relay HRR₁ to the west line ML'.

The breaking arrangement for each side of the intermediate repeater set operate on the same general principle as the breaking arrangements for the terminal sets which have been heretofore described. At the intermediate station C, however, there are three different conditions under which breaking occurs. These conditions are as follows: One distant station breaking the intermediate station, one distant station breaking the other distant station through the intermediate set, and the intermediate station breaking a distant station. The operation of the arrangements under these three conditions will now be described.

When the intermediate station C is transmitting signals to the terminal stations and when one distant station, taking, for example, the west one, such as station A, desires to stop or break the intermediate station's sending, the operator at the west station will, open his break key and send out a positive impulse. This positive impulse, meet-

ing the next negative one from the intermediate station, will cause double current to flow in the west line ML. This double current will operate the west break relay WBR, thus closing the following circuit; from negative battery through the winding of the sender switching relay SSR, left front contact of the break control relay BCR, front contact of the west break relay WBR, winding of the west transfer relay WTR, left back contact of the east transfer relay ETR and break key BK₁ to positive battery. The sender switching relay SSR and the west transfer relay WTR will now operate, the west transfer relay WTR locking up by means of its right front contact through the winding of the sender switching relay SSR, a back contact of the east transfer relay ETR and the break key BK₁. The sender switching relay short-circuits the sending distributor SD and connects the armature and contact of the receiving relay RR₁ in series with the pole changer circuit. The west line ML will now be disconnected from the sending pole changer PC₁ and connected to the receiving relay RR₁ by the operation of the west transfer relay WTR. The spacing or break impulse from the west station, such as station A, will cause the armature of the receiving relay RR₁ to open the pole changer circuit so that a spacing signal will be repeated to the east line ML', the home record relay HRR₁, sending an open signal into the printer set which will operate the printer break relay or otherwise stop the sending. This spacing signal will continue to be received until the west station's break key is closed. The circuit will now be in position for sending from the west station. A similar operation takes place when the east station breaks the intermediate set.

With the west station, such as station A, sending, the east station, such as station B, may break by sending out a spacing signal in the usual manner which will operate the east break relay EBR when a marking impulse is sent over the east line. The east break relay EBR in operating closes the following circuit: from positive battery through the break key BK₁, right front contact of break control relay BCR, front contact of east break relay EBR, winding of east transfer relay ETR, back contact of west break relay WBR, left front contact of break control relay BCR, winding of sender switching relay SSR to negative battery. The simultaneous operation of the east break and transfer relays opens the locking circuit of the west transfer relay, thus releasing it so that the west line ML will be connected to the sending pole changer PC₁. The sender switching relay SSR will remain operated in series with the locking circuit of the east transfer relay ETR. The

operation of the east transfer relay disconnects the east sending apparatus and connects the receiving relay RR, to the east line ML'. The spacing impulse from the 5 east station will cause the receiving relay RR, to open the circuit of the pole changer so that it will send a spacing signal over the west line ML. This causes a break signal to be sent to the west station, operating 10 the break relay BR at that station and the west break relay WBR at the intermediate station. The west transfer relay WTR at the intermediate station will not operate at this time, as its operating circuit is open at 15 the left front contacts of the break control relay BCR, owing to the fact that the pole changer circuit is open. The operation of the transfer relay TR at the west station will put the system in position so that signals 20 from the east station, such as station B, will be received at the intermediate station C and repeated to the west station, such as station A. In case station A should break station B, the operation would be correspondingly the same. 25

Let it be assumed, now, that the east station, such as station B, is sending and that the intermediate station C wishes to send. The intermediate station operator will open 30 his break key BK₁, releasing the east transfer relay ETR and the sender switching relay SSR and at the same time opening the pole changer circuit so that a spacing impulse will be sent out. This spacing signal, meeting a marking impulse from station B, will operate the break relay BR' at station B and the east break relay EBR at the intermediate station. The operation of the break relay at station B places that station 35 in position to receive while at the intermediate station nothing happens as the circuit through the east transfer relay ETR is open at the front contact of the break control relay BCR and at the break key BK₁. As the west station, such as station A, had been receiving before the intermediate station broke, no other action than the receipt of a spacing signal will take place at that station. Thus, after the break key BK₁ has 40 been closed the intermediate set may start to send. The operation would have been similar had station A been sending and the intermediate station desired to break said station. 45

It is pointed out that the sender switch relay SSR operates in series with either of the transfer relays WTR and ETR and short-circuits the sending apparatus. Consequently, the intermediate station operator 50 must always operate his break key BK₁ before he can send, provided that he has previously been receiving. This prevents the operator from sending out in only one direction as would be the case had he neglected to first break. The sender switching 55

relay SSR also short-circuits the receiving relay contacts when the intermediate set is sending, making it unnecessary to provide means for holding the receiving relay armature against its marking contact at this time. 70 The repeater cut-off relay COR is supplied with battery from a source at station C, such as the generator of the pole changer PC. If this source should fail the relay COR will release and connect the stations 75 A and B directly with each other.

While the arrangements of the invention have been disclosed in certain specific arrangements which are deemed desirable it is understood that they are capable of embodiment in many and other widely varied forms without departing from the spirit of the invention as defined in the appended claims. 80

What is claimed is: 85

1. In a signaling system, a line circuit, a repeater station associated with said line circuit and terminal stations associated with each end of said line circuit, transmitting apparatus and receiving apparatus at each terminal station, a pole changer transmitter and a polar receiving relay at said repeater station, an operating circuit for said pole changer transmitter controlled over the contacts of said polar receiving relay, and switching means at said repeater station whereby said polar receiving relay may be connected to either section of said line and said pole changer transmitter may be connected to the other section of said line. 95

2. In a signaling system, a line circuit, a repeater station associated with said line circuit and terminal stations associated with each end of said line circuit, transmitting apparatus and receiving apparatus at each terminal station, a pole changer transmitter and a polar receiving relay at said repeater station, an operating circuit for said pole changer transmitter controlled over the contacts of said polar receiving relay, switching means at said repeater station whereby said polar receiving relay may be connected to either section of said line and said pole changer transmitter may be connected to the other section of said line, and means unresponsive to normal signaling currents but responsive to abnormal current conditions of the line for controlling said switching means. 110

3. In a signaling system, a line circuit, a repeater station associated with said line circuit and terminal stations associated with each end of said line circuit, transmitting apparatus at said repeater station, sending means for controlling said repeater transmitting apparatus, receiving apparatus at said repeater station, means for operatively connecting said repeater transmitting apparatus to both of the sections of said line at the same time, and switching means for dis- 120 125 130

- connecting one of said line sections from said repeater transmitting apparatus and connecting said line section to said repeater receiving apparatus.
6. 4. In a signaling system, a line circuit, a repeater station associated with said line circuit and terminal stations associated with each end of said line circuit, transmitting and receiving apparatus at each terminal
- 10 station, transmitting apparatus at said repeater station, sending means for controlling said repeater transmitting apparatus, receiving apparatus at said repeater station, means for operatively connecting said repeater transmitting apparatus to both of the sections of said line at the same time, switching means for disconnecting one of said line sections from said repeater transmitting apparatus and connecting said line section to said repeater receiving apparatus, and means controlled by said last mentioned means whereby control over said repeater transmitting apparatus may be transferred from said sending means to said repeater receiving apparatus.
- 25 5. In a signaling system, a line circuit, a repeater station associated with said line circuit and terminal stations associated with each end of said line circuit, said repeater
- 30 station comprising a pole changer transmitter common to both of the sections of said line, a polar receiving relay, means for controlling said pole changer by said receiving relay, and switching means controllable from either terminal station for connecting said receiving relay to either line section and said pole changer to the other line section.
- 35 6. In a signaling system, a line circuit, a repeater station associated with said line circuit and terminal stations associated with each end of said line circuit, said repeater
- 40 station comprising a transmitting device common to both of the sections of said line, a source of current for said transmitting device, a receiving device, means for controlling said transmitting device by said receiving device, switching means controllable from either terminal station for connecting said receiving device to either line section and said transmitting device to the other line section, and a cut-off relay for connecting said line sections to said repeater station, said relay being normally energized from said source of current for said repeater transmitting device and an auxiliary circuit closed upon the deenergization of said cut-off relay for connecting said line sections directly together.
- 45 7. In a signaling system, a line circuit, a repeater station associated with said line circuit and terminal stations associated with each end of said line circuit, transmitting apparatus at said repeater station, sending means for controlling said repeater transmitting apparatus, receiving apparatus at said repeater station, means for normally operatively connecting said repeater transmitting apparatus to both of the sections of said line at the same time, switching means for disconnecting one of said line sections from said repeater transmitting apparatus and connecting said line section to said repeater receiving apparatus, and a break key at said repeater station for restoring said switching means to normal whereby said transmitting apparatus may again be connected to both of said line sections.
- 50 75 In testimony whereof, we have signed our names to this specification this 22nd day of May, 1922.
- GILBERT S. VERNAM.
EDWARD F. WATSON.
